UNITED STATES PATENT OFFICE.

HENRY W. AVERY, OF CLEVELAND, OHIO.

NON-REFILLABLE RECEPTACLE.

SPECIFICATION forming part of Letters Patent No. 745,988, dated December 8, 1908.

Application filed December 21, 1901. Serial No. 86,727. (No model.)

To all whom it may concern:

Be it known that I, HENRY W. AVERY, a citizen of the United States, residing at Cleveland, in the county of Cuyahoga and State of Ohio, have invented a certain new and useful Improvement in Non-Refillable Receptacles, of which the following is full, clear, and exact description, reference being had to the accompanying drawings.

10 My invention relates to means for preventing the refilling of bottles, jugs, &c., after they have once been emptied. It comprehends a valve mechanism so operating and held in the neck of the receptacle by some suitable 15 baffle. Such baffles are illustrated in my prior patents, No. 670,266, granted to me March 19, 1901, and No. 688,574, granted to me December 10, 1901.

Assuming that a suitable baffle is applied 20 to the neck, preventing the removal of the valve structure or interference with its action, the present invention provides this valve structure in a form which shall be very simple, while being efficient to prevent refilling 25 in all positions of the bottle. The valve structure comprises two balls, a lower light ball and an upper relatively heavy ball, contained within a chamber formed in the neck, which is so shaped that when the bottle or receptacle is on its side or out of the vertical position the heavier ball rolling down an incline will, by gravity, force the lighter ball ahead of it toward its seat, where any incoming liquid will snugly seat it. Thus if the bottle is 30 inverted it cannot be refilled, for the light ball will float against its seat and prevent entrance, while if the bottle stands upright the heavy ball resting on the light ball will hold it down to its seat, and if the bottle is 35 held sidewise the same action will follow by the heavy ball rolling down the incline of the neck.

It has heretofore been attempted to use the 40 light and heavy ball with a plug in the neck 45 of the vessel, providing an incline for the heavy ball; but so far as I am aware these balls have not been confined within a surrounding neck so formed as to itself present the incline by which the heavy ball insures 50 the sealing of the light ball.

My construction is of advantage, as it requires no extra parts whatever besides the two

balls and is independent of the form of baffle employed. It allows the use of the simplest form of baffle, as shown herein.

The chambered neck operating as above described is an essential element of the combination constituting the present invention, as hereinafter more fully explained, and definitely set out in the claim.

The drawings clearly illustrate my invention, wherein—

Figure 1 is a vertical central section of a non-refillable bottle embodying the invention and provided with a baffle of substantially 55 the form set out in my Patent No. 688,574. Fig. 2 is a view of the same, the bottle being on its side. Fig. 3 is a plan of the baffle.

The bottle or other receptacle is designated A. It has a neck portion with a curved chamber a' , as shown. Above this is an enlargement a' , and above this is the cork portion a^2 .

B represents the light ball and C the heavy ball. These occupy the chamber a , as shown, being prevented from leaving the same by 75 the baffle D, which, as shown, is a thin plate adapted to be bent on its diameter and dropped through the neck portion a^2 and then flattened by pressure into the form shown in Figs. 1 and 2. Thereafter a cork E is placed 80 in the neck portion. Now the valve B and C does not prevent the exit of the liquid, which when the bottle is tipped up passes out under the light ball B and over the heavy ball C, as shown by dotted lines in Fig. 2, 85 whence the liquid escapes through the scalloped openings d of the baffle. When it is attempted to refill the bottle, however, it will be seen that in any position approximating an upright position the heavy ball will rest on 90 the light and hold it to its seat. If the bottle be completely inverted, the light ball B would float on the liquid and prevent the entrance. When the bottle is on its side, either horizontally or near enough thereto so that the liquid 95 might pass into the interior and the air escape therefrom, the ball C rolling down the incline of the chamber forces the ball B ahead of it toward its seat. This action is aided by the force of the incoming liquid which will 100 snugly seat the light ball. Thus in every position of the receptacle admission is prevented.

By making the chamber a an integral por-

tion of the neck I simplify and cheapen the construction, enabling the bottle to be blown in an ordinary mold and doing away with any cemented plugs or other arrangements which 5 are expensive and liable to contaminate the contents. As is well known, bottles blown in the same mold vary considerably in thickness, and consequently any tight-fitting plugs or cemented devices have to be especially 10 formed for each bottle or the bottle ground for the plug, which in either case causes a considerable expense. Moreover, there is always danger of the cement working loose or dissolving in the contents of the bottle. 15 By my method the chamber is simply blown and does not have to be accurate. There is no subsequent finishing or grinding and no cement, as there is not nicety of fit required at any point. Finally, I am enabled to use 20 a baffle designed solely with reference to its capabilities as a baffle without its being hampered by having to form a portion of the valve structure.

The light ball B may be made of cork, the 25 heavy ball C of glass, and the baffle D of metal, though other materials may be employed, if desired. The upper end of the chamber is somewhat larger than the lower end to allow convenient access of the two 30 balls from above. I also find it convenient to make the heavier ball the larger of the two. The baffle D may be marked with a

trade-mark or other proprietary data to prevent any substitution for it if it should be removed.

It will be observed that the interior of the chamber *a* is curved inwardly at the upper portion thereof to form a shoulder *a*³ and that the depth of the chamber from the shoulder to the valve-seat is substantially equal to the 40 combined diameters of the balls B and C. By this construction the weighting-ball C operates readily when the bottle is in a horizontal position to seat the valve-ball B.

I claim—

A non-refillable bottle having a neck formed integral therewith and comprising a chamber provided with a valve-seat at the lower portion thereof, said chamber having a continuous concave interior surface extending inwardly at the upper portion thereof to form a shoulder, an enlargement above said shoulder, a retaining-baffle in said enlargement, a stopper-receiving portion above said enlargement, and a light valve-plug and a weighting-ball in said chamber, substantially as described.

In testimony whereof I hereunto affix my signature in the presence of two witnesses.

HENRY W. AVERY.
